UNITED STATES PATENT OFFICE.

E. LANSO DUNKLEE, OF WYALUSING, PENNSYLVANIA.

THILL-COUPING.

SPECIFICATION forming part of Letters Patent No. 359,011, dated March 8, 1887.

Application filed September 7, 1886. Serial No. 212,927. (No model.)

To all whom it may concern:

Be it known that I, E. LANSO DUNKLEE, of Wyalusing, in the county of Bradford and State of Pennsylvania, have invented a new and Improved Thill-Coupling, of which the following is a full, clear, and exact description.

My invention relates to thill-couplings, and has for its object to provide a simple, inexpensive, substantial, readily-adjustable, and non-rattling coupling of this character.

The invention consists in certain novel features of construction and combinations of parts of the thill-coupling, all as hereinafter fully described and claimed.

Reference is to be had to the accompanying drawings, forming a part of this specification, in which similar letters of reference indicate corresponding parts in both the figures.

Figure 1 is a side view of my improved coupling as attached to an axle, which is shown in cross-section, the thill-iron being broken away; and Fig. 2 is a front view of the coupling and adjacent portion of the axle.

The main body part or bow A of the thill-coupling which embraces the vehicle-axle B is provided, as usual, with bolt ends *a a*, which pass through the lower clip-plate, C, and receive tightening-nuts D E below said plate.

A lug, F, formed on the front of the coupling-bow A, has a round transverse aperture, *f*, in which the eye or rounded lug *g* of the thill-iron G has a bearing. At its top or upper part the lug F is cut away to form a transverse slot, *f'*, only about broad enough for the shank portion *g'* of the thill-iron next its eye *g* to pass through, and into this transverse slot *f'* there opens a front vertical slot, H, which is formed in the top and front portions of the coupling-lug F, and in which slot H the shank *g'* of the thill-iron rests when the thills are down with their forward ends on the ground, or when the thills are raised somewhat and a horse is hitched to the vehicle between them.

The eye *g* of the thill-iron G is about as long as or a trifle longer than the width of the lug F, in which it fits, and at its opposite ends the eye is provided with pins I I, over which hooks J J, formed on the upper ends of an open yoke or link, K, are engaged. A

nut E, is bent over downward and then forward, and at its outer or forward end is provided with a hook, M, which engages the lower cross-bar, *k*, of the link K, and exerts 55 a constant downward pressure on said link, and through its hooks J and the pins I upon the eye *g* of the thill-iron, and prevents rattling of the eye in its bearing-lug F; hence the coupling will be noiseless. Furthermore, 60 the lapping of the sides of the link K upon opposite sides or faces of the lug F and the thill-iron eye *g* tends to hold the parts of the coupling together.

To uncouple the thills, it is only necessary 65 to lift the links K against the tension of the springs L and disengage the link-hooks J from the pins I of the thill-iron eyes, and when the thills are raised until their shanks *g'* stand in line with the top transverse slots, *f'*, of the 70 lugs F, and as indicated in dotted lines in Fig. 1, the thills may be disconnected by moving them to one side or the other, the shanks of the thill-irons then slipping through the slots.

To couple the thills to the axle, the shanks *g'* of the thill-irons will be brought to coincide with the lug-slots *f'*, and the thills will be moved sidewise until their shanks *g'* come into line with the lug-slots H, and the thills 80 then will be lowered to enter the shanks *g'* into said slots H, and the hooks J of the link K will be engaged with the thill-iron pins I, and the coupling is complete.

This thill-coupling, while being practically 85 noiseless, is very easily adjusted and is reliable in use, and is not expensive, and has a neat appearance on the running-gear of a vehicle, and there is no danger of accidental disengagement of the thills from the vehicle. 90

Having thus fully described my invention, what I claim as new, and desire to secure by Letters Patent, is—

1. The combination, in a thill-coupling, of a clip device adapted to a vehicle-axle and 95 provided with a lug, as at F, having a transverse hole, *f*, and slot *f'*, and a vertically-ranging slot, H, opening into slot *f'*, a thill-iron having an eye or lug, *g*, fitting the hole *f* in lug F, and provided with lateral projections, as at I I, a link, K, having hooks J J engaging the projections I I, and a spring draw-

ing on the link for holding the eye *g* to a bearing in the clip-lug *F*, substantially as herein set forth.

2. The combination, in a thill-coupling, of 5 a clip device, as at A C D E, adapted to a vehicle-axle and provided with a lug, *E*, having a transverse hole, *f*, and a slot, *f'*, and a vertically-ranging slot, *H*, opening into slot *f'*, a thill-iron, as at *G*, having an eye or lug, *g*, 10 fitting the hole *f* of lug *F*, and provided with

lateral projections, as at I I, and a spring, *L*, held to the clip device or axle, and having a hook end, *M*, engaging the links *K*, for holding the thill-iron eye *g* to a bearing in the clip-lug *F*, substantially as herein set forth.

E. LANSON DUNKLEE.
